FAUCET HANDLE

Mark B. Botefur, Fullerton, Stephen J. Kelsey, Granada Hills, and Harold J. Valley, Rolling Hills, Calif., assignors to Martin Marietta Aluminum Inc.

Filed Aug. 27, 1971, Ser. No. 175,802

Term of patent 14 years

Int. Cl. D23—01

U.S. Cl. D23—28

FIG. 1

FIG. 2

FIG. 3

FIG. 4

FIG. 1 is a top plan view of a faucet handle embodying our new design;

FIG. 2 is a side elevational view thereof;

FIG. 3 is a bottom plan view thereof; and

FIG. 4 is a top plan view of another form of the faucet handle shown in FIG. 1.

We claim:

The ornamental design for a faucet handle, as shown and described.
